UNITED STATES PATENT OFFICE.

GEORGE I. ROCKWOOD, OF WORCESTER, MASSACHUSETTS.

DRY-PIPE SPRINKLER SYSTEM.

1,199,744.

Specification of Letters Patent. Patented Sept. 26, 1916.

Application filed November 24, 1915. Serial No. 63,294.

To all whom it may concern:

Be it known that I, GEORGE I. ROCKWOOD, a citizen of the United States, residing at Worcester, in the county of Worcester and 5 State of Massachusetts, have invented a new and useful Dry-Pipe Sprinkler System, of which the following is a specification.

Although the so-called dry pipe sprinkler system is largely employed at the present 10 time, a serious difficulty is presented occasionally when this system is used in a cold storage plant. It has been found that water will condense on the inside of the pipes and owing to the low temperature in the cold 15 storage plant will freeze there and eventually fill up the pipe, thus preventing its proper operation. I have found that this difficulty is due to the fact that the small body of water used for sealing the valve of 20 the dry pipe vaporizes slowly and the vapor extends throughout the riser pipe and the piping system connected with it.

The principal object of this invention is to prevent the passage of water vapor 25 through the riser pipe and the system and I accomplish this result according to the present invention by recondensing the vapor at a point close to its source and directing it back into the body of water from which it 30 is supplied.

Reference is to be had to the accompanying drawing, which is a central vertical 35 sectional view of a portion of a dry pipe sprinkler system showing a preferred embodiment of this invention applied thereto.

The drawing shows the invention as applied to a dry pipe sprinkler system comprising the usual supply main 10, dry pipe valve 11, air supply pipe 12 and alarm pipe 40 13. Ordinarily the riser pipe 14 is connected directly above this valve but according to this invention a separate conductor 15 is provided. I prefer to make this in the form of a cone having its small end connected 45 with the valve and the large end with the riser pipe 14. Inside this cone is located a conical core 16 spaced from the walls and consequently providing an annular passage for the air and also, of course, for the water 50 to the system. This core is shown as firmly supported by a rod 17 at the top and bottom

and preferably is made hollow. Surrounding this core, but spaced from it, is a condensing coil 18. This is designed to be fed by a pipe 19 from the outside and to discharge at the top through a pipe 20 back into this pipe 19. These pipes are kept supplied with water by means of a water tank 21 having a float 22 for operating a valve 23 and keeping a constant head of water in 55 the tank, which is supplied from a supply pipe 24. It will be noticed that the distance between the core 16 and inner surface of the conductor 15 decreases from the bottom to the top. This is to provide substantially 60 a uniform area in cross section at all levels so that all the vapor passing through cannot fail to come under the influence of the condensing coil.

For the purpose of cooling the pipe 19 70 from a source outside the conductor 15 and thus causing a continuous circulation of cold water down through the pipe 19 and up through the condensing coil, I have shown a casing 25 surrounding this pipe 19 and 75 provided with supply and discharge pipes 26 and 27. This is for cooling purposes and it may be supplied with a cooling mixture, but preferably is supplied with a cooling liquid through the pipe 26. 80

For the purpose of regulating the temperature of the condensing coil I have shown a chamber 30 connected with the pipe 19 and provided with a diaphragm 31 therein, the interior of which is filled with ether 85 or a gas or vapor that is readily expansible by heat and not condensable except at temperatures below those required here. The temperature of the water in the chamber 30 surrounding this diaphragm, controls the 90 contraction and expansion of the ether and causes the diaphragm to move back and forth and operate a rod 32. By means of a bell crank 34 and connections 35 this operates an arm 36 on a valve 37 in the pipe 26. 95 In this way when the temperature is reduced below the predetermined degree the flow of cooling liquid through the pipe 26 to the chamber 25 will be reduced. I have also shown a thermometer 40 located in a convenient position and having its bulb in a 100 chamber communicating with the pipe 19 so

as to show at all times the temperature of the liquid passing into the condensing coil.

As the cooled liquid circulates through the coil 18 any vapor that arises from the water sealing the dry pipe valve will have to go into the annular passage in the conductor 15 and be subjected to the action of the condensing coil. It will be seen, therefore, that the condensed liquid will flow down the walls of the conductor 15 or of the core and will drop back into the body of sealing water. This prevents any large quantity of vapor from passing into the riser pipe and thus into the sprinkler system and maintains the same in a substantially dry condition except when it is operated. In this simple and inexpensive manner water vapor is kept out of the system, and the danger of the pipes becoming stopped by ice is substantially avoided and thus the dry pipe sprinkler system is rendered suitable and safe for use in cold storage plants and the like.

The pipe 19 can be located in one of the cooling chambers of the cold storage plant which will provide all necessary cooling effect. Although the condensing coil is cooled it will not be frozen by this means.

Although I have illustrated only a single form of the invention I am aware of the fact that modifications can be made therein by any person skilled in the art without departing from the scope of the invention as expressed in the claims. Therefore, I do not wish to be limited to the details herein shown and described, but

What I do claim is:—

1. In a sprinkler system of the dry pipe type, the combination with a riser pipe normally filled with air, a water supplying means, and a valve for normally closing connection between them, of means for condensing the moisture contained in the air in the pipe to prevent the moisture from passing along the pipe and being condensed on the inner surface thereof.

2. In a sprinkler system, the combination with a pipe normally filled with air, a water supply main, and a valve for normally closing connection between them, of means between said valve and the pipe for condensing the moisture contained in the air at the end of the pipe.

3. In a dry pipe sprinkler system, the combination with a riser pipe, a supply main, and a valve for normally closing connection between them, of means between said valve and the riser pipe for condensing the moisture contained in the air passing to the riser pipe, and directing it back toward said valve.

4. The combination with a sprinkler system of the dry pipe type, of a conductor at the inlet end thereof having a narrow space

for the air, and a condensing coil located in said space.

5. In a sprinkler system of the dry pipe type the combination with a riser pipe, of a conical conductor at the inlet end thereof having an annular space for the air, and a condensing coil located in said annular space.

6. In a sprinkler system of the dry pipe type the combination with a conductor having an annular space for the air, a condensing coil located in said annular space, a pipe for conducting a cooling liquid to the bottom of said coil, and a pipe for conducting liquid away from the top of the coil, said pipes being connected outside the conductor.

7. In a sprinkler system, the combination with a conical conductor, of a conical core in said conductor forming an annular space therewith for the passage of air, a coil located in said space, a pipe for conducting water into the bottom of said coil outside the conductor, means for cooling the water in said pipe before it passes into the coil, means for conducting the water from the other end of the coil back to the pipe above said cooling means, and means for maintaining a full supply of water in said pipes and coil.

8. In a sprinkler system of the dry pipe type, the combination with a supply main, and a riser pipe, of a conductor connecting them, said conductor having a space extending therethrough provided with a cross sectional area substantially equal to the area of the supply main, and means in said space for condensing vapor in the air therein.

9. In a sprinkler system of the dry pipe type, the combination with a supply main, and a riser pipe, of a conductor connecting them, said conductor having slanting walls and having a space extending therethrough provided with a cross sectional area substantially uniform from one end to the other and substantially equal to the area of the supply main, and means in said space for condensing vapor in the air therein and allowing it to run down said slanting walls.

10. In a sprinkler system of the dry pipe type, the combination with a conductor, of a condensing coil located in said conductor, a pipe for conducting the liquid into said condensing coil, a chamber surrounding said pipe, means for conducting a cooling liquid into said chamber, and means whereby when the temperature of the liquid in said pipe gets down to a predetermined minimum the rate of flow of the cooling liquid to said chamber will be reduced.

11. In a sprinkler system of the dry pipe type, the combination with a conductor having an annular space for the air, of a condensing coil located in said annular space, a pipe for conducting the liquid into said con-

densing coil, a chamber surrounding said pipe, means for conducting a cooling liquid into said chamber, a casing to which said pipe is connected, a diaphragm located in 5 said casing and having an expansible fluid behind it, a valve for controlling the supply of cooling fluid to said casing along said con-

ducting means, and means whereby as said fluid is condensed the valve will be brought farther toward its closed position. 10

In testimony whereof I have hereunto set my hand.

GEORGE I. ROCKWOOD.
